SPRAY HEAD

Gale H. Buzzard and Robert W. Tracy, Toledo,
Ohio, assignor to The De Vilbiss Company,
Toledo, Ohio, a corporation of Ohio

Application January 16, 1932, Serial No. 586,984

11 Claims. (Cl. 299—140.1)

This invention relates to a spray head primarily adapted for use in spray coating.

The object of the invention is to provide improved means for shaping the spray stream as it leaves the nozzle and more particularly to provide a spray having a clearly defined pattern with little or no spattering or overspray about the main body of the pattern.

The invention will be more specifically explained in connection with the accompanying drawing, in which—

Figure 1 is a front elevation of the spray head;
Figure 2 is a longitudinal section taken on the line 2—2 of Fig. 1;

Figure 3 is a partial section taken on the line 3—3 of Fig. 1;

Figure 4 is an enlarged sectional view of the tip of the fluid nozzle;

Figure 5 represents a spray pattern as hitherto produced by a spray head with flattening jets, but without the shaping means provided by the present invention; and

Figure 6 represents a spray pattern produced by a spray head constructed according to the present invention.

Our invention is adapted for use in various types of spray heads. In the adaptation herein shown, the head comprises an inner fluid nozzle 8 formed with a tip 9 through which the coating material is emitted and an outer nozzle 10 which controls the air. The rear end portion of the nozzle 8 is enlarged as shown at 11 and is connected in any suitable manner with the body of the spray gun 12. The enlarged portion 11 of the nozzle 8 is formed with a suitable seat 13 against which the air nozzle 10 is held by a union nut 14 or other suitable means.

The fluid tip 9 is provided with an orifice 15 through which the emission of the spray material is controlled by a needle 16. The central outer portion of air nozzle 10 is in the form of a cap enclosing an air space 17 having a main discharge orifice 18 surrounding the fluid tip 9.

The nozzle 10 is also provided with a pair of forwardly and outwardly projecting horns 19 provided with oppositely disposed orifices 20 through which flattening air jets are discharged at an angle to the spray stream in a well known manner.

In accordance with our invention, the central cap-like portion of the air nozzle 10 is also provided with a pair of opposed orifices 21 disposed in a plane at right angles to the plane of the orifices 20. The diameter of the orifices 21 is about one-half that of the orifices 20 and they are also lo-

cated comparatively close to the main air orifice 18 and have a smaller angle of convergence than the orifices 20 so that the air jets emitted from the orifices 21 impinge at a comparatively small angle against the spray stream between the fluid tip 9 and the region in which the flattening jets from the orifices 20 engage and flatten the spray stream.

It will also be noted that the outer end surface of the fluid tip 9 is in the same plane with the outer surface of the air nozzle 10 and is provided with a circumferential edge 22 slightly rounded on a curve of .020" radius. Preferably the diameter of the orifice 18 is about .152" and the diameter of each orifice 21 is .039" while the diameter of each orifice 20 is .078". The axes of the orifices 21 are at an inclination of 20° to the axis of the fluid nozzle and the axes of the orifices 20 are at an inclination of 50° to the axis of the nozzle.

In the operation of a spray head constructed in accordance with our invention, the smaller air jets from the orifices 21 impinge against the spray stream between the end of the tip 9 and the vertex of the flattening jets from the orifices 20. These smaller jets with their comparatively small angle of convergence slightly flatten or smooth out the spray along the sides which later become the edges of the spray stream when the latter is flattened by the larger air jets. In other words, the smaller jets tend to clean up the edges of the fan spray so that it produces the pattern shown in Fig. 6, eliminating the spatter and overspray which would otherwise produce a pattern like that shown in Fig. 5.

The smaller jets also add to the atomizing air emitted from the orifice 18 in such a manner as to reduce the forward blow of the center air. This reduction of velocity helps to eliminate the wavy effect which occasionally appears as a result of the force with which the spray hits the surface being coated.

The rounded edge 22 tends to promote a smoother flow of the air from the orifice 18 and thus to clean up the pattern all around.

While we have described in considerable detail the preferred form of the invention, it is obvious that the same may be considerably modified without departing materially from the scope of the appended claims.

What is claimed is:

1. A spray head comprising means for discharging air and material to form a spray stream, means for discharging separate supplemental convergent air jets against opposite sides of the

- 5 spray stream to flatten the same, and means for supplemental jets and nearer to the spray head than discharging other supplemental air jets against the first mentioned jets, to lessen the spattering opposite sides of the stream in a plane at right from the edges of the stream as flattened by the angles to the plane of the first mentioned supplemental jets and with a smaller angle of convergence to lessen the spattering from the edges first mentioned supplemental jets.
- 10 6. A spray head comprising means for dis- 7. A spray head comprising an outer air nozzle, means for discharging separate supplemental air jets against opposite sides of the spray stream to flatten the same, and means for causing other supplemental air jets to impinge against the stream in a plane at right angles to the plane of the first mentioned supplemental jets and nearer to the spray head than the first mentioned jets, to lessen the spattering from the edges of the stream as flattened by the first mentioned supplemental jets.
- 15 8. A spray head comprising means for dis- 9. A spray head comprising means to discharge charging air and material to form a spray stream, an air supported stream of coating liquid, means means for discharging separate supplemental air jets against opposite sides of the spray stream to flatten the same, and means for discharging other supplemental air jets against opposite sides of the stream in a plane at right angles to the plane of the first mentioned supplemental jets and nearer to the spray head than the first mentioned jets, said other opposed orifices being of less diameter than the first mentioned supplemental orifices.
- 20 10. A spray head comprising means to dis- 11. A spray head comprising means to dis- charge an air supported stream of coating liquid, means for discharging separate supplemental air jets acting on said stream to form the same, and means for discharging other supplemental air jets against opposite sides of the stream in a plane at right angles to the plane of the first mentioned supplemental jets and nearer to the spray head than the first mentioned jets, said other opposed orifices being of less diameter than the diameter of the first mentioned supplemental orifices.
- 25 12. A spray head comprising means for dis- 13. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and nearer to the spray head than the first mentioned jets, said other supplemental jets being smaller than the first mentioned jets.
- 30 14. A spray head comprising means for dis- 15. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and nearer to the spray head than the first mentioned jets, said other supplemental jets being smaller than the first mentioned jets.
- 35 16. A spray head comprising means for dis- 17. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and nearer to the spray head than the first mentioned jets, said other supplemental jets being smaller than the first mentioned jets.
- 40 18. A spray head comprising means for dis- 19. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and nearer to the spray head than the first mentioned jets, said other supplemental jets being smaller than the first mentioned jets.
- 45 20. A spray head comprising means for dis- 21. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and nearer to the spray head than the first mentioned jets, said other supplemental jets being smaller than the first mentioned jets.
- 50 22. A spray head comprising means for dis- 23. A spray head comprising means to dis- charging air and material to form a spray stream, charge an air supported stream of coating liquid, means means for discharging supplemental air jets against opposite sides of the stream to flatten the same, and means for causing other supplemental air jets to impinge against the stream in a plane at right angles to the plane of the first mentioned supplemental jets and with a smaller angle of convergence.
- 55 24. A spray head comprising means for dis- 25. A spray head comprising means to dis- charging air and material to form a spray stream, charge an air supported stream of coating liquid, means means for discharging supplemental air jets against opposite sides of the stream to flatten the same, and other opposed orifices for discharging supplemental convergent air jets against opposite sides of the spray stream to flatten the same and other opposed orifices for discharging supplemental jets against the spray stream in a plane at right angles to the plane of the first mentioned supplemental jets and with a smaller angle of convergence.
- 60 26. A spray head comprising means for dis- 27. A spray head comprising means to dis- charging air and material to form a spray stream, charge an air supported stream of coating liquid, means means for discharging supplemental air jets against opposite sides of the stream to flatten the same, and other opposed orifices for discharging supplemental air jets against opposite sides of the spray stream to flatten the same, and other opposed orifices so disposed as to emit jets which
- 65 28. A spray head comprising means for dis- 29. A spray head comprising means to dis- charging air and material to form a spray stream, charge an air supported stream of coating liquid, means means for discharging supplemental air jets against opposite sides of the stream to flatten the same, and other opposed orifices so disposed as to emit jets which impinge against the stream in a plane at right angles to the plane of the first mentioned supplemental jets.

CERTIFICATE OF CORRECTION.

Patent No. 2,004,033.

June 4, 1935.

GALE H. BUZZARD, ET AL.

It is hereby certified that error appears in the printed specification of the above numbered patent requiring correction as follows: Page 2, first column, line 33, claim 4, after "discharging" insert the word separate; and line 34, before "stream" insert the word spray; same page and column, line 60, and second column, lines 9 and 23, claims 6, 7 and 8 respectively, after "with" insert the words a main orifice concentrically surrounding said material nozzle and with; and that the said Letters Patent should be read with these corrections therein that the same may conform to the record of the case in the Patent Office.

Signed and sealed this 16th day of July, A. D. 1935.
